UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

WORK-POSITIONING DEVICE FOR BUTTONHOLE-SEWING MACHINES.

1,359,712.

Specification of Letters Patent. Patented Nov. 23, 1920.

Application filed May 6, 1920. Serial No. 379,375.

To all whom it may concern:

Be it known that I, JOHN KIEWICZ, a citizen of the United States, residing at Boston, county of Suffolk, State of Massachusetts, have invented an Improvement in Work-Positioning Devices for Buttonhole-Sewing Machines, of which the following description, in connection with the accompanying drawing, is a specification, like characters on the drawing representing like parts.

This invention relates to buttonhole sewing machines and particularly to sewing machines that are adapted to sew the buttonholes in the backs of collars, and the main object of the invention is to provide a novel work-holding device by which the collar is automatically centered so as to insure that the buttonhole will be made at the proper position centrally at the back of the collar.

In order to give an understanding of my invention, I have illustrated in the drawings a selected embodiment thereof which will now be described, after which the novel features will be pointed out in the appended claims.

In the drawings, Figure 1 is a plan view of a portion of the bed plate and work-holding means of a buttonhole sewing machine showing my improvement applied thereto;

Fig. 2 is a section on the line 2—2, Fig. 1;

Fig. 3 is a section on the line 3—3, Fig. 2;

Fig. 4 is a section on the line 4—4, Fig. 1;

Fig. 5 is a section on the line 5—5, Fig. 1.

Inasmuch as my present invention relates simply to the work-holding means, I have not thought it necessary to illustrate a complete buttonhole sewing machine.

1 indicates the front portion of the bed frame of a buttonhole sewing machine, and 2 is the clamp plate of the work-clamping means on which the work is clamped by means of the work clamps 3 that are pivoted to the clamp plate, as usual in buttonhole sewing machines. The clamp plate has the usual sewing opening 4 immediately beneath which is situated the throat-plate 5 of the under-thread-handling mechanism, and the work-clamp 3 is provided with an elongated opening 6 corresponding to the length of the buttonhole to be made.

The work-holding means comprising the clamp plate 2 and work-clamp 3 are mounted for movement toward and from the front

of the bed plate 1 thereby to carry the work from buttonhole-cutting to stitching position and vice versa, and it is also mounted for movement transversely of the bed plate 1 or in the direction of the length of the opening 6 thereby to provide for feeding the work down one side of the buttonhole and then back the other side thereof. The work-holding means is shown in Fig. 1 in its buttonhole-cutting position, and when the sewing machine is started, the buttonhole is cut, after which the work-holding means is moved forwardly to bring the throat-plate 5 underneath the opening 6, after which the stitching on the buttonhole is done in usual manner.

The buttonhole sewing machine herein shown is constructed to stitch the button-hole at the back of a collar, the latter being shown in dotted lines at 7. In order to properly stitch this buttonhole it is, of course, essential that during the stitching operation the collar should be so positioned that the back buttonhole when formed will be in the right location relative to the buttonholes at the end of the collar indicated by the dotted lines 48, and my improvements are directed to a novel means for positioning the collar when it is first inserted into the machine and before the work clamps 3 are closed thereby clamping the collar against the clamp plate 2.

My improved positioning device is automatic in its action so that all the operator has to do is to attach the collar thereto, the device automatically acting to center the collar and insure that it is properly positioned before it is clamped.

The positioning device herein shown and which constitutes the preferred embodiment of my invention comprises as one element thereof a plate 8 which overlies the bed plate 1 of the machine and is detachably secured thereto in some suitable way. I have herein shown for this purpose clamping screws 9 extending through open slots 49 formed in said plate and screw-threaded into the bed frame 1, and a retaining arm 50 depending from the front of the plate 8 and underlying the flange 51 of the bed frame, said arm 50 having a spring-pressed retaining pin 52 adapted to enter a recess in said flange 51. This pin 52 is provided with a head 53 by which it may be withdrawn from the recess when the plate 8 is

to be removed. Said positioning device also comprises two arms 10 pivotally connected to the plate 8 at 11 and provided at their free ends with projections or pins 12 adapted to enter the buttonholes 48 of the collar. These pins or projections 12 are adjustably mounted in slots 13 formed in the ends of the arms 10 so as to permit the pins to be adjusted longitudinally of the slots. Said pins when adjusted are clamped in adjusted position by clamping screws 14.

The arms 10 are spring-actuated and are capable of swinging toward and from each other about their pivots 11 and they are also connected by suitable connections which compel them to move in unison and in equal amounts but in opposite directions.

Each arm is pivotally connected by a link 15 to a slide 16 which is supported by the plate 8 and is constructed to slide toward and from the front of the bed plate 1 or at right angles to the front edge 17 of the plate 8. Suitable means are provided for guiding the slide 16 in its sliding movement so that it will always move at right angles to the edge 17. For this purpose, I have provided said slide 16 with a guiding slot 18 and have also provided a guiding member 20 which is provided with a guiding fin 21 that enters the slot 18, said guiding member 20 being secured to the plate 8 by suitable screws 19. With this construction the sliding movement of the slide 16 in a direction at right angles to the edge 17 will operate through the links 15 to swing the arms 10 about their pivots 11, and because both arms are linked to the slide 16 said arms must always swing in unison and to the same extent.

The slide 16 is acted upon by a spring finger 22 which is anchored at one end to the plate 8, as shown at 23. This finger tends to move the slide into the full line position thereby separating the arms 10.

In applying a collar to the positioning device, the slide 16 is moved forwardly into the dotted line position thereby swinging the arms 10 toward each other, and the end buttonholes 48 of the collar 7 are then inserted over the pins 12, the center portion of the collar being inserted beneath the raised clamp 3. 24 is a back gage by which the back edge of the collar is properly positioned in a direction from front to back. After the collar has been placed on the pins 12, the slide 16 is released and the spring 22 moves it toward the rear thereby separating the arms 10 as far as the length of the collar will permit. This separating movement of the arms 10 serves to place the collar under slight tension and to straighten it, and because of the manner in which the arms are connected, the portion of the collar which is situated beneath the opening 6 of the work clamp will always be midway be-

tween the pins 12 and thus midway between the buttonholes 48. After the collar has thus been placed on the pins and the slide 16 has been released, the operator then starts the machine in usual manner, thereby causing the work-clamps 3 to descend and clamp the collar in this position. With my improvements, therefore, the collar will be always properly positioned by merely placing it on the pins 12, as above described.

When the sewing machine is started the first operation is to close the work-clamps 3 onto the work and then the clamp plate 2 is moved forwardly so as to bring the portion underneath the opening 6 into stitching position, as usual in buttonhole sewing machines. During the stitching on the buttonhole, the work clamp is given a back-and-forth feeding movement in the direction of the length of the collar, and since the plate 8 is secured to the stationary bed plate 1, the feeding movement of the clamp plate will be a movement relative to the stationary plate 8. In order to provide for this, I employ a construction which will automatically produce a slack in the portion of the collar between the ends and the clamped central portion thereof after the work clamps 3 are closed thereby permitting the central portion of the collar where the buttonhole is to be formed to be moved back and forth relative to the ends of the collar.

The slide 16 has fast thereto a finger 25 which extends underneath the plate 8 and occupies a groove 30 formed in the bed plate 1. This finger 25 is situated to be engaged by the end of the clamp plate 2 when the latter moves from its buttonhole-cutting position to the stitching position, and, therefore, the shifting of the clamp plate 2 into stitching position will move the slide 16 forwardly into the dotted line position thereby swinging the arms 10 toward each other and providing considerable slackness in the collar between the ends thereof and the portion which is clamped by the work clamp 3. This movement of the slide 16 which is caused by the clamp plate 2 does not occur, however, until after the work clamps 3 have been closed onto the positioned collar so that the swinging of the arms 10 after the work clamp is closed has no effect in disturbing the proper position of the portion of the collar where the buttonhole is to be formed.

In order to permit the device to be used on collars of different sizes, I propose to make each arm 10 in two sections, one section indicated at 26 being pivoted at 11 and having the link 15 pivotally connected thereto at 27, and the other section 28 being pivoted on the section 26 at 29 and carrying at its free end the pin 12. The section 28 is provided at one end with a slot 30 through which a clamping screw 31 extends, said screw screw-

threading into the section 26. By loosening the screw 31 the section 28 carrying the pin can be adjusted relative to the section 26, and by making the proper adjustment in both arms the pins can be arranged the appropriate distance apart for any size of collar.

The manner in which the device operates will be apparent from the foregoing. In placing the collar in the sewing machine, the operator will first pull the slide 16 forwardly, thereby swinging the arms 10 inwardly to a point that will permit the end buttonholes 48 of the collar to be inserted over the pins 12, after which the slide will be released and the spring 22 will automatically move the arms 10 away from each other thereby straightening the collar and bringing the central portion thereof directly beneath the opening 6 of the work clamp. Any suitable means may be provided to thus operate the slide 16. It will be possible to manipulate said slide with a foot-lever or with a hand-lever or directly by the hand. It is immaterial how this is done so far as this invention is concerned.

After the collar has been thus positioned, the button-hole sewing machine is started which results in first closing the work clamps 3 onto the collar, then cutting the button-hole, then shifting the work clamp from buttonhole-cutting to stitching position and stitching the buttonhole. The shifting of the work clamp from cutting to stitching position acts through the arm 25 to again move the slide 16 forwardly into the dotted line position thereby providing sufficient slack in the collar to permit the transverse feeding movement of the central portion thereof.

After the buttonhole is stitched and the clamp has been released, the operator can then readily remove the collar from the pins 12.

While I have illustrated a selected embodiment of my invention, yet I do not wish to be limited to the constructional features shown.

I claim:

1. In a buttonhole sewing machine of the type having a bed plate and work-holding means arranged to move toward the front of the bed plate thereby to carry the work from buttonhole-cutting to stitching position and also to move laterally to give the work a feeding movement, the combination with said bed plate and work-holding means, of two collar-holding elements situated on opposite sides of the work-holding means, a connection between said elements by which they are caused to move toward and from each other in unison and by which they tend normally to separate from each other whereby a collar secured to said elements will be held under tension and posi-

tioned centrally, and means to cause said elements to move toward each other when the work-holding means shifts the work from buttonhole-cutting to stitching position.

2. In a sewing machine of the class described, the combination with a bed plate and work-holding means movable toward the front of the bed plate to carry the work from buttonhole-cutting to stitching position, of a plate secured to the bed plate, collar-positioning arms pivotally mounted to the ends of the plate and adapted to engage the ends of a collar, and a spring-actuated connection between said arms which tends normally to separate them and which operates to hold the collar retained by said arms in central position.

3. In a sewing machine of the class described, the combination with a bed plate and work-holding means movable toward the front of the bed plate to carry the work from buttonhole-cutting to stitching position, of a plate secured to the bed plate, collar-positioning arms pivotally mounted to the ends of the plate and adapted to engage the ends of a collar, a slide mounted on said plate and movable toward and from the front thereof, and a connection between said slide and arms whereby the movement of the slide causes the arms to move in unison but oppositely.

4. In a sewing machine, of the class described, the combination with a bed plate and work-holding means movable toward the front of the bed plate to carry the work from buttonhole-cutting to stitching position, of a plate secured to the bed plate, collar-positioning arms pivotally mounted to the ends of the plate and adapted to engage the ends of a collar, a slide mounted on said plate and movable toward and from the front thereof, a connection between said slide and arms whereby the movement of the slide causes the arms to move in unison but oppositely, and a spring acting on said slide and tending to move it in a direction to separate said arms.

5. In a sewing machine of the class described, the combination with a bed plate and work-holding means movable toward the front of the bed plate to carry the work from buttonhole-cutting to stitching position, of a plate secured to the bed plate, collar-positioning arms pivotally mounted to the ends of the plate and adapted to engage the ends of a collar, a slide mounted on said plate and movable toward and from the front thereof, a connection between said slide and arms whereby the movement of the slide causes the arms to move in unison but oppositely, a spring acting on said slide and tending to move it in a direction to separate said arms, and means actuated by the movement of the work-holding means from

buttonhole-cutting to stitching position to move the slide forwardly.

6. In a buttonhole sewing machine of the class described, the combination with a bed plate, of work-holding means movable toward the front of the bed plate to carry the work from buttonhole-cutting to stitching position and also movable transversely to give the work feeding movement, said
- 10 work-holding means having provision for clamping the work, collar-holding means carried by the bed plate and constructed to engage the ends of a collar and hold it taut and also to place the collar in central position, and means whereby movement of the work-holding means from buttonhole-cutting to stitching position after the work is clamped moves the collar-holding means to give slack to the ends of the collar thereby
- 15 to permit the work-holding means to have its lateral work-feeding movement.
- 20

7. In a buttonhole sewing machine of the class described, the combination with a bed plate, of work-holding means movable toward the front of the bed plate to carry 25 the work from buttonhole-cutting to stitching position, a plate secured to the bed plate, a collar-holding arm pivoted to each end of said plate, a slide mounted on said plate and movable toward and from the front thereof, a link connecting said slide with each arm whereby forward movement of the slide swings the arms toward each other, a spring tending to move the slide rearwardly thereby to separate the arms, and 30 a finger connected to said slide and situated to be engaged by the work-holding means during its forward movement.

In testimony whereof I have signed my name to this specification.

JOHN KIEWICZ.
